DIE FORGING PRESSES

Samuel J. Fuchs, New York, N.Y.

Application May 18, 1956, Serial No. 585,879

3 Claims. (Cl. 78—44)

This invention relates to die forging presses, especially heavy presses, and a method of operating them.

The die parts usually called die blocks, which are the members in direct contact with the work being formed or forged, and the die sets, one of which is inserted between each die block and a platen of the press, are usually fabricated of high strength alloy steel. On the other hand the platens and their supporting beams, because of their large extent, are usually made of ordinary structural steel for economic reasons. The die sets are prismatic blocks which transmit the force applied by the platens to the die.

To make the die sets thick enough so that when they are under load by the action of the press, they do not subject the die blocks or platens, especially the latter, to unequal stress distribution would be uneconomical because of the high cost of high strength alloy steel.

The use of relatively thin die sets tends to result in excessive concentration of stress on the platens with consequent indentation and permanent set of their surface where it contacts the die sets.

It is an object of the present invention to make such provision that the economy of using thin die sets can be effected. It is proposed to accomplish this by providing mating surfaces, between the die set and the platen, so formed relatively to each other as to eliminate or equalize substantially the unequal stress noted above. There are a number of ways in which this can be done. For example, the mating surface of the die set can be suitably concaved toward the platen, the mating surface of the platen can be suitably concaved toward the die set, or the relative configurations of said mating surfaces can be such as to provide a suitable cavity. In its broadest sense suitable space is to be provided which tends to close up to reduce or eliminate unequal distribution of stress upon the platen when the pressure is applied by the press.

An object of the invention is the mitigation of the accentuated stresses prevailing in present construction in proximity to the central portion of the die set-platen interface.

My preferred way is to use an insert or lamination with a concave surface between the die set and platen, keeping the surfaces of the die set and platen plane because of shop difficulties in handling such cumbersome pieces as die sets and platens. Said concave surface preferably forms a depression or cavity which is greatest at its central portion, tapering off to zero at its periphery.

Other objects and advantages will become apparent upon further study of the specification and drawings, in which:

Fig. 1 is a conventionalized or diagrammatic end view of the working parts of a typical heavy capacity die forging press except that it shows inserts or laminations provided between the die sets and platens in accordance with the preferred form of my invention.

2

Fig. 2 is a section of the press taken along the line 2—2 of Fig. 1 but with the foundation omitted and the two center rods broken off for clarity.

Fig. 3 is an enlarged partial elevation of the press of 5 Fig. 1 showing only the lower die block, die set, insert and a broken away portion of the platen before the pressure is applied by the press.

Fig. 4 is an enlarged partial section, along the line 10 4—4 of Fig. 3, through the lower die set, insert and platen before the pressure is applied by the press. The insert or lamination is concave toward the bottom.

Fig. 5 is a similar section to that of Fig. 4 but shows conditions after the load or pressure has been applied, the die set having become convex downward at its lower 15 surface.

Fig. 6 is a diagram showing the various pressures under consideration.

Fig. 7 is a partial section taken similarly to Fig. 4 but with a modified insert, the modification of the insert 20 consisting in providing it with a concavity or depression both in its top and in its bottom.

Fig. 8 is a partial section taken similarly to Fig. 4 but modified by the provision of two inserts with suitable 25 cavities.

Fig. 9 is a partial section taken similarly to Fig. 4 but without the provision of an insert, the concavity being provided on the bottom of the die set itself, and

Fig. 10 is a partial section taken similarly to Fig. 4 but without the provision of an insert, the cavity being 30 provided in the platen.

Referring to Figs. 1 and 2, which show the preferred form of my invention embodied in a die forging press, the die blocks 10 and 11 are supported as in the usual practice by die sets 12 and 13. Die sets 12 and 13 are 35 essentially prismatic blocks of high strength alloy steel, which transmit the pressure developed by the press upon die blocks 10 and 11 through upper and lower inserts or laminations 14 and 15 to the upper and lower platens 16 and 17 respectively.

Upper cross beams 18 are in operative relation to upper platen 16. Lower cross beams 19 are in operative relation to lower platen 17 and support the press by resting on foundation 20. Cross beams 19 are stationary, while upper cross beams 18 and additional or lowermost 40

cross beams 22 are movable. There is a cross beam 22 in vertical alignment with each pair of cross beams 18 and 19. Each upper cross beam 18 has a tie rod 23 extending between it and a lowermost cross beam 22. Said tie rods are slidably mounted in beams 19. Ex- 45

tending between each pair of cross beams 19 and 22 are hydraulic cylinders 24. As is well known in the art when cylinders 24 force down their piston rods or rams 25, upper die block 10 is forced down to lower die block 11 compressing whatever work that may have been set 50 between said blocks.

When die set 13 is subjected to pressure, Fig. 6, where the die set 13 is shown in mating contact with a plane surface, because of the flexibility of said die set and die block 11, the line of pressure is that shown by curve 60 BAB, the pressure being greatest near A. This would result for usual die set proportions in producing heavier pressure toward the center of any work being forged in die block 11 and subject the platen 17 to a greater intensity of pressure locally. However, if a cavity BDBCB were provided, the excess pressure in the vicinity of A would be relieved by the deflection of die set 13 but the pressure would be increased toward regions 65 B. If the proper form of cavity were provided, the pressure would be uniform as shown by line FGF. It is an object of the invention to produce such uniform pressure.

70

In the foregoing description of the development of stress distribution according to the invention, the assumption was made of a concentrically uniform intensity of load delivered to the die set from the die block. This is the industrially important case corresponding substantially to the majority of industrial applications. Where, however, the applied load is eccentric, that is, it is shifted to one side with respect to the axis of the die set, the function and construction of the parts to provide a cavity or cavities is the same as described herein except that the preformed hollowed out surface or surfaces is asymmetrically modified, the central portion of the cavity or cavities being correspondingly shifted to one side with respect to the die set.

As noted before, the cavity or cavities can be provided in a number of different ways. Referring to Figs. 3, 4 and 5, insert 15 is shown located between die set 13 and platen 17. Insert 15 is concaved on the bottom. In Figs. 3 and 4 no pressure has been applied by the press so that the cavity 26 is visible. The bottom of die set 13 is plane. Upon the application of pressure, cavity 26 disappears, Fig. 5, the lower surface of die set 13 becoming substantially convex downward.

In Fig. 7 an insert 27 is shown located between die set 13 and platen 17. Insert 27 is provided with a cavity 28 in its upper surface and a cavity 29 in its lower surface. These two cavities together function in a similar manner to the single cavity 26 of Fig. 3.

In Fig. 8 an upper insert 30 is provided with a cavity 31 in its lower surface and a lower insert 32 is provided with a cavity 33 in its lower surface. These cavities together are the equivalent of the single cavity 26 of Fig. 3.

In Fig. 9, die set 13 is provided with a cavity 34 which closes up when pressure is applied resulting in equal distribution of stress.

In Fig. 10, platen 17 is provided with a cavity 35 which closes up when pressure is applied resulting in equal distribution of stress.

The cavities noted above may be supplied either for the upper assembly of the press with its platen 16, die block 10 and die set 12 or for the lower assembly with its platen 17, die block 11 and die set 13 or the cavities may be applied for both the upper and lower assemblies of the press.

With all the various forms of inserts or laminations such as inserts or laminations 14, 15, 27, 30 and 32, there exists the common feature of an equivalent aggregate thickness of hollow space included between die set and platen in the unloaded condition, which is elastically closeable under load. As noted before, the mating surfaces between die set and platen can also be preformed to achieve the same result of hollow included space, but the accurate preparation of the surfaces of these massive members into the required contour would be cumbersome and inconvenient.

The depth of the hollow space or cavity diminishes

generally from that at the central portion, distance DC Fig. 6, to the perimeter of the cavity. Said depth is of an amount calculated to result in the desired stress distribution or equalization of stress under load at the mating surfaces of the die set and the platen. The numerical data required for the determination of the depth at each coordinate point of the hollow space or cavity may be obtained in advance by calculation but preferably by a series of tests with scale models of gypsum, glass, or other elastic materials. From the numerical data so obtained, the required contoured surface can be fabricated by those skilled in the art.

I claim:

1. Lamination means adapted to be set intermediate of the die block and the platen of a press, said means being of varied thickness, being thinner at its central portion than toward its edges to allow the die block to deflect elastically more at the central portion than towards the edges when pressure is applied to it by the press, so as to result in substantial equalization of pressure on the platen.

2. In a press, a construction provided intermediate of the die set and the platen of the press, said construction having mating surfaces formed to provide space between them, said space being deeper at some portions than at others to allow the die set, when pressure is applied to it by the press, to deflect elastically more at the deeper portions than at others, so as to effect equalization of pressure on the platen, said space being provided by the relative form of the mating surfaces of the platen and the die set, the mating surface of the platen being substantially flat and that of the die set concaved.

3. In a press, a construction provided intermediate of the die set and the platen of the press, said construction having mating surfaces formed to provide space between them, said space being deeper at some portions than at others to allow the die set when pressure is applied to it by the press, to deflect elastically more at the deeper portions than at others, so as to effect equalization of pressure on the platen, said space being provided by the relative form of the mating surfaces of the platen and the die set, the mating surface of the die set being substantially flat and that of the platen concaved.
